FIG. 3

FIG. 4

FIG. 5

FIG. 6

FIG. 7

FIG. 8

FIG. 10

FIG. 9

Edna M. Franklin
INVENTOR.

right shoulders, respectively, of a wearer and are preferably of such length that they may be extended forwardly and downwardly over the respective left and right front sections of the wearer for fastening by means of suitable fasteners 3 and 5, respectively, adjacent their respective ends, to the upper edge portion of a conventional brassiere 70 (Fig. 3).

The garment A may be formed of any suitable material and is preferably made in at least three sizes, for example, small, medium and large. Adjacent their ends 9 and 18 the respective sections F and G are provided with a row of suitable cooperating fasteners 12 and 14, respectively, for holding the sections in overlapping engagement. To compensate for variations in the waist measurement of each individual size I have provided an elastic-like cord fastened by a tape 13 to the outer surface of the band-like section G and arranged to define loops 16 which are engageable with the fasteners 12 for providing resilient adjustment of the garment around a wearer (Fig. 9).

As an additional aid in maintaining the garment in snug fitting contact with the body of a wearer I have provided a loop 26 connected to the right side of the garment adjacent the juncture of the section F with the right side of the garment to which one end of a resilient or elastic cord 22 is connected. A hook-like fastener 24 is connected to the free end of the cord. The length of the cord 22 is such that it may be stretched slightly and span the front portion of the body of a wearer across the bustline and be connected by the hook fastener 24 to a loop 20 similar to the loop 24 and similarly connected to the left side of the garment.

The garment A may be made with various modifications for use with different types of dresses, for example, the bight of the U-shaped upper portion may be lowered in a manner defined by the dotted line 29 (Fig. 1), for use with a low backed dress. Similarly this portion may be lowered still further, as shown by the dotted line 30, for use with dresses having a still lower back line leaving relatively narrow tapering shoulder bands designated as D and E. Fig. 5 illustrates these two modifications. Similarly the garment A may be formed with tapering waist band extensions, as by removing the end and upper edge portions of the extensions F and G along the dotted lines 32 and 33, respectively, for using the garment in combination with the garment illustrated in Fig. 2, as will be more fully explained hereinbelow. It seems obvious that the garment A may be formed without the upwardly extending U-shaped portion, as by defining the upper edge thereof along the dotted line position 31, for use of this garment with strapless or sleeveless evening gowns as exemplified by Fig. 8.

Referring now more particularly to Fig. 2, the reference character H designates, as a whole, a substantially triangular shaped member defined by the lines 46, 54 and 56. The opposing ends of the member H lying outwardly of the lines 58 and 59, respectively, are adapted to be extended around the body of a wearer at the normal waistline position in end overlapping relation and be adjustably fastened together as by suitable fastening means 48-49 and 50, 52 carried by the respective ends of the member H (Fig. 7). Two similar bust covering sections L and M are cooperatively sewed together along the center front line X-Y which extends upwardly from the apex of the triangular shaped member H. The lines 60, 64 and 62 define the respective arcuate outer and upper edges of the sections L and M. The respective lower edges of the sections L and M are sewed to the respective upper edges 54 and 56 of the member H with the material of the sections gathered at suitable locations, as indicated at 66, for providing fullness of the garment.

This completes the front bodice member, as illustrated in Fig. 2 formed of any suitable material, and which is adapted, when in use, to cover the front bodice portion of the body of a wearer extending upwardly

from the normal waistline, occupied by the lower edge 46 of the garment, up to and covering the bustline including a brassiere as is clearly shown in Fig. 6. The uppermost edge or tip portions of the sections L and M are provided with loop-like fasteners 40 and 38, respectively, for connection with the uppermost edge of the brassiere 70 and for other purposes which will presently be apparent.

The back and front bodice members as shown by Figs. 1 and 2 may be worn separately as shown by Figs. 3 and 6, respectively, or they may be worn as a combination as is shown by Fig. 10. When worn in combination the back bodice garment A is first positioned on the body of a wearer, as disclosed hereinabove, and the front bodice member is then positioned to overlie the band-like sections F and G and a portion of the under-arm areas of the wearer. When worn as a combination garment the shoulder bands are connected by the fasteners 3 and 5 to the fasteners 38 and 40. The elastic band 22 is removed and the loops 20 and 26 are connected with suitable fasteners 42 and 44 attached to the under-arm side edges of the sections M and L respectively, thus effecting a supporting connection for the side portions of both the back and front bodice members.

Thus it may be seen that I have provided a back and front bodice garment which will substantially envelop or cover the area of the body underlying various types of bodice outer garments and which will therefore serve as a perspiration absorbent and will further act as an aid in preventing contact of the skin of the wearer with fabrics to which the wearer may be allergic.

Obviously the invention is susceptible to some change or alteration without defeating its practicability, and I therefore do not wish to be confined to the preferred embodiment shown in the drawings and described herein further than I am limited by the scope of the appended claim.

I claim:

A bodice garment, comprising: a bodice front garment and a bodice back garment, said back garment including a central section adapted to cover the back and underarm side bodice portions of a wearer and extend from the waistline to the back neck line and having a pair of shoulder bands each having side edges converging toward its free end and adapted to extend forwardly and downwardly over the shoulders of the wearer and terminating at a point substantially coincident at the armpits of the wearer when positioned thereon, said back garment having a pair of band-like extensions integrally joined with the lower back portion thereof and adapted to extend around the body of the wearer when positioned thereon in end overlapping relation below a line between the armpits and upwardly of the waistline; adjustable fastening means carried by said band-like extensions for connecting the same together, said front garment comprising a substantially triangular shaped section adapted to surround the wearer at the waistline with the apex of the triangular shape extending upward of the wearer's waistline when positioned thereon and a pair of connected bust covering sections carried by the upper edges of said triangular shaped section and adapted to extend upwardly therefrom to a point substantially coincident at the armpits for covering the bust of the wearer when positioned thereon; and fasteners carried by the respective free ends of said shoulder bands and the uppermost edge of said front garment for connecting said shoulder bands to said front garment.
